DESIGN FOR A PLASTIC SHEET OR SIMILAR ARTICLE

Edmund H. Tyson, Caldwell, N. J., assignor, by mesne assignments, to E. I. du Pont de Nemours & Company, Wilmington, Del., a corporation of Delaware

Application July 15, 1936, Serial No. 63,861

Term of patent 7 years

To all whom it may concern:

Be it known that I, Edmund H. Tyson, a citizen of the United States and a resident of Caldwell, in the county of Essex, and State of New Jersey, have invented a certain new, original, and ornamental Design for a Plastic Sheet or Similar Article, of which the following is a specification, reference being had to the accompanying drawing, forming part thereof.

In the accompanying drawing:—

Figure 1 is a plan view of a plastic sheet or similar article bent into the form of a tube and showing my new design; and

Figure 2 is a plan view of a flat plastic sheet or similar article showing my new design.

The dominant feature of my design is the ornamentation appearing on the sheet and is independent of the thickness and configuration of the sheet.

I claim:—

The ornamental design for a plastic sheet or similar article, substantially as shown and described.

EDMUND H. TYSON.
